(57) **CLAIM**

The ornamental design for the biochemical analyzer, as shown and described.

DESCRIPTION

FIG. 1 is a front, top and right side perspective view of a biochemical analyzer showing a first embodiment of my new design and where the convex portion thereof is translucent;

FIG. 2 is a front elevational view thereof;

FIG. 3 is a rear elevational view thereof;

FIG. 4 is a top plan view thereof;

FIG. 5 is a bottom plan view thereof;

FIG. 6 is left side elevational view thereof;

FIG. 7 is a right side elevational view thereof;

FIG. 8 is a front, top and right side perspective view of a biochemical analyzer showing a second embodiment of my new design and where the convex portion is opaque;

FIG. 9 is a front elevational view thereof;

FIG. 10 is a rear elevational view thereof;

FIG. 11 is a top plan view thereof;

FIG. 12 is a bottom plan view thereof;

FIG. 13 is left side elevational view thereof; and,

FIG. 14 is a right side elevational view thereof.

The broken lines shown in the drawings represent portions of the biochemical analyzer that form no part of the claimed design.
